[57] CLAIM

The ornamental design for a joy stick console for remote position and engine control of a crane or the like, as shown.

DESCRIPTION

FIG. 1 is a perspective view of the joy stick console for remote position and engine control of a crane showing my new design;

FIG. 2 is a top plan view thereof;

FIG. 3 is a left side elevation view thereof;

FIG. 4 is a front end elevation view thereof;

FIG. 5 is a rear end elevation view thereof;

FIG. 6 is a bottom plan view thereof; and

FIG. 7 is a right side elevation view thereof.
